ROBERT J. KEHL, OF CHICAGO, ILLINOIS, ASSIGNOR, BY MESNE ASSIGNMENTS, TO THE LIBBEY GLASS MANUFACTURING COMPANY, OF TOLEDO, OHIO, A CORPORATION OF OHIO.

METHOD OF AND APPARATUS FOR CUTTING OFF WASTE ENDS OF INCANDESCENT LAMP BULBS.

Application filed October 3, 1921. Serial No. 505,154.

This invention relates to a method of and apparatus for cutting-off or severing the waste ends from the stems or necks of incandescent lamp bulbs, but it will be understood that the method and apparatus disclosed may also be utilized for the removal of parts from other tubular articles.

The relatively heavy waste mass, generally known as the moil, at the end of the stem or neck of a machine-blown incandescent lamp bulb has heretofore been removed by methods and machines which are not entirely satisfactory. By one method known as the heating-and-cracking-off method, the bulb is heated at the line of severing and then brought into contact with a cold body, which causes the end to crack off. The edge of the bulb must then be re-heated to make it smooth and prevent checking, but even then many are cracked, checked, and otherwise rendered worthless. By another method known as the melting-off method, the bulb is heated at the line of severing until it softens sufficiently so that the weight of the waste end separates it from the bulb proper. Removing the waste end by this method takes considerable time and gas, and the edge usually needs to be re-heated and shaped with a reamer or other tool.

Various types of machines have heretofore also been employed to carry out the foregoing methods. In the continuous travel apparatus, a continuously revolving carrier continuously moves the bulbs past the heating and auxiliary devices, the bulbs at the same time rotating about their own vertically disposed longitudinal axes. In the intermittent travel apparatus an intermittently operating carrier moves the bulb from one operation to the next, the bulb being rotated as in the continuous travel apparatus. In the single operation apparatus, a bulb is fed into a fixture and revolved until the heating and removing operation is completed whereupon it is removed.

Subjecting the bulb to a succession of operations or to a flame which heats the bulb until the waste end drops off, requires considerable time and gas, and the principal object of this invention is therefore, to provide a method and apparatus that shall be more economical in operation. According

to the present invention, the lamp bulb is supported so that its main axis is vertical, with the waste end thereof lowermost, and the bulb is then rotated about such axis while the latter is stationary, with the cutting line on the neck thereof between heating and cutting gas flames of an intensity adapted to first heat the neck along such line and then quickly puncture or slit it to an extent to sufficiently weaken the connecting section so that the weight of the waste end exceeds the adhesion or strength of the remaining connecting section, whereupon the waste end quickly drops off. The temperature of the gas flames may be comparatively low for this operation, or comparatively high if desired, the gas flames being so adjusted as to provide sharp cutting points, producing a very localized fusion (herein called severing or cutting) as distinguished from the heating up and gradual fusion which takes place when ordinary flames are used, which will quickly puncture the neck after it has been slightly heated along the cutting-off line. The glass along the line of severance is thus melted so quickly that severance results and leaves the glass constituting the severed edge of the finished article in substantially its original position with regard to the portion of the said article to which it is attached. The improved apparatus for carrying out the improved method broadly comprises mechanism for suspending the lamp bulb with its waste end lowermost, and rotating the bulb about its vertical axis while the waste end is being cut off. The cutting-off means comprises pointed gas flames, desirably groups of such flames, symmetrically arranged in a horizontal plane about the axis of rotation of the bulb and opposite the line of junction of the waste end and the neck proper, and so arranged that the tips of the flames will touch and heat the bulb along said line and then quickly cut, slit, or puncture it along the cutting-off line, as distinguished from fusing off such end. By this method and apparatus the waste or moil end is effectively and quickly removed in a single operation, resulting in considerable economy of time and gas. The entire cutting operation is done in one setting and the possi-

bility of heating different zones is therefore eliminated.

The object and the novel features of the invention will be apparent from the following description taken in connection with the drawings, in which

Fig. 1 is a vertical sectional view of an apparatus embodying the present invention and adapted to carry out the improved 10 method,

Fig. 2 is a perspective view of an improved burner employed in the apparatus and method of the present invention.

Fig. 3 is a horizontal sectional view of 15 the burner of Fig. 2, taken through the burner nozzles thereof, and

Fig. 4 illustrates another apparatus embodying this invention and capable of performing the improved method.

Various mechanisms may be employed to handle machine-blown incandescent lamp bulbs or similar articles and properly present them to a cutting-off burner, and the mechanisms shown in the drawing are, therefore, merely illustrative. Referring to Fig. 1, a suitable support, such as table T, has bearings for rotatably mounting a vertical shaft S carrying a turret R parallel to and above the table, the shaft S being adapted 20 to be rotated intermittently, as by a Geneva gear G operated by a suitable power shaft P through suitable gearing and a counter-shaft S'. The turret R is provided with a series of chucks C, each adapted to receive 25 a machine-blown incandescent lamp bulb L from suitable feeding mechanism (not shown) and suspend it with its main axis vertical, and rotate it about such vertical axis, as through suitable shafting S" and 30 gearing K and K'.

Incandescent lamp bulbs, as blown in a machine, usually have relatively heavy waste masses, otherwise known as moils, at the ends of the stems or necks thereof. In 40 the machine-blown bulb illustrated in Fig. 1, for example, the relatively heavy waste mass W is shown at the lower end of the neck N, and before the bulb may be utilized in lamp manufacture, it is necessary to remove this waste end along a line A. This 45 end has heretofore been removed by various methods and machines, as described, which are objectionable because of the high percentage of defective bulbs produced, compara- 50 tively poor finish of edge, and the time and gas required. According to the present invention, the lamp bulb L is rotated about the axis of the burner and the flames, and the latter first heat the neck along the line 55 A and then quickly slit or puncture it so that the connecting section is sufficiently weakened to permit the weight of the waste end to overcome the adhesion of the remaining connection and drop off by gravity.

60 The mechanism of Fig. 1 intermittently

presents rotating lamp bulbs to the cutting-off burner B with the axis of the lamp bulb coinciding with the axis of the burner and the cutting-off line disposed in the same horizontal plane with and opposite to and 65 practically touching the tips of the gas flames of the burner B. The burner employed may be of any suitable construction, the one illustrated in Figs. 1, 2 and 3 being especially suitable for the apparatus disclosed in Fig. 1 wherein the bulb is moved into cutting-off position from the side, while the burner shown in Fig. 4 is of a type adapted for the insertion of the lamp bulb, 70 axially from above. Referring to Figs. 1, 2 and 3, the improved burner illustrated comprises a header or casting having parallel base members 15 and 16 provided with screw holes 17 whereby the burner may be secured to the table T. Pairs of upright 75 members 19, 20 and 21, 22 rise from the ends of the bases 15, and 16 the upper ends of the uprights 19, 21, and 20, 22 being connected by the bridges 23, 24, respectively. As illustrated in Fig. 3, the inner opposed sides 80 of the bridges 23 and 24 have curved faces 231 and 241 respectively, whose center of curvature is in the vertical axis of the burner. The outer side of the bridge 24 is provided with a gas inlet passage 25 to which a suitable gas supply device or mixer 85 M may be coupled. The faces 231 and 241 are provided with groups of outlets 26, 27 which are connected to the main inlet gas 90 passage 25 by suitable gas passages D connected together and extending through the several sections of the burner casting. The outlets 26 and 27 may have burner nozzles 95 28 and 29 detachably and adjustably coupled thereto, as by screw-threaded stems fitting 100 in threaded portions of said outlets. The groups of burner nozzles 28 and 29 are arranged symmetrically with respect to the axis of the burner and on diametrically 105 opposite sides thereof, as shown, being disposed within an arc of about 60°. The intermittently rotating carrier or turret R thus carries the bulb laterally into the burner through one side of the latter and out again at the opposite side, the neck, of the bulb 110 passing into the working position between the uprights 19, 20 and 21, 22, and the stationary groups of nozzles 28 and 29 therein, so that flames may be directed from two 115 sides toward the rotating bulb at the severing or working position within the burner. Each burner nozzle has a passage that tapers to its orifice so it will project a pointed flame radially towards the axis of the burner, the burner nozzle being adjusted so 120 that the tip of the high temperature flames will practically just touch the wall of the neck N at the cutting-off line A. The groups of flames on each side of the axis in effect thus provide two arcs of flames for 125 130

heating and puncturing the neck of the lamp bulb. The distance between the groups of burner nozzles is, of course, determined by the size of the neck of the lamp bulb to be operated upon, different lengths of burner nozzles being insertable in the outlets 26 and 27. The speed of rotation of the lamp bulb and the pressure of the gas supplied by the burner nozzles are also factors determining 5 the time of heating and puncturing the necks. The pressure of the mixture of the gases issuing from the tips is desirably between 6 and 12 ounces per square inch, and the temperature and visual properties of 10 the cutting flame are desirably those characteristic of oxidizing oxy-fuel gas flames. For example, it has been found that for a lamp bulb having a neck about one and three-fourths inches in diameter at the cutting-off line A, the best speed of rotation is 15 about thirty revolutions per minute, if an oxidizing flame having a tip pressure between 6 and 12 ounces per square inch is employed. The kind of gas used also plays 20 an important part in the number of burners in each group and the particular distance they are separated. For oxy-hydrogen, oxy-city gas, oxy-natural gas, etc. flames (comparatively low temperature flames) each 25 group of burners desirably consists of three burners spaced about 30° apart, as illustrated in Figs. 1, 2 and 3, while for oxy-acetylene flames (high temperature flames) two groups 30 are employed with two burners in each 35 group spaced about 60° apart.

The burner casting may also be provided with suitable cooling-water connections 31 and 32 to circulate cooling water through suitable connected passages E in the several 40 sections of the burner casting.

Fig. 4 illustrates a burner B' embodying the principles of this invention but in which the lamp bulb L' is inserted from above into the chuck C' and into the space within 45 the burner in position to be operated upon by the flames. Suitable mechanism may be provided for successively presenting the bulbs to the chuck C' and for rotating the latter and the lamp bulb L' about the vertical axis of the burner B'. The burner B' 50 as illustrated, is provided with groups of burner nozzles 28' and 29' similar to those shown in Figs. 1, 2 and 3, but the sides and ends of the casting are in the same plan, 55 otherwise the adjustment and operation of this burner and the apparatus associated with it are similar to the apparatus shown in Figs. 1, 2 and 3.

Guards F may be secured to the burner 60 castings, or headers, desirably to the tops of the nozzle-carrying sections thereof, and extend inwardly over and slightly beyond the tips of the groups of nozzles 28 and 29 a sufficient distance to protect the nozzles 65 from damage. Furthermore, the mixing

and gas supply device M may have a cooling-water passage m that may be connected in series with the passages E of the burner by pipes 311 and 321 so that the cooling-water may be circulated through the mixing device and header successively, avoiding extra piping end connections. 70

The operation and advantages of the improved method and apparatus will be apparent from the foregoing description. While 75 the invention has been shown and described in detail, it will be understood that various changes may be made in the constructions herein disclosed without departing from the principles of the invention or sacrificing any 80 of the advantages thereof.

I claim:

1. The method of cutting off a part of a tubular article at one setting which comprises supporting said article at a station so that 85 its main axis is vertical and said part is at its lower end and with the temperature of the article substantially uniform and rotating said article at said station about such vertical axis and between heating and cutting gas flames adapted to heat said article along a circumferential line or zone and then puncture it along said line at the said station to an extent to sufficiently weaken the connecting section so that the weight of said 90 part overcomes the adhesion of said part to the main part of the article and said part drops off.

2. The method of cutting off a part of a tubular article at one setting and in a single 100 operation which comprises supporting said article so that its main axis is vertical and said part is at its lower end and with the temperature of the article substantially uniform and rotating said article about a fixed 105 vertical axis coinciding with its main axis and between heating and cutting gas flames arranged symmetrically and in groups on opposite sides of said fixed axis and adapted to heat said article along a circumferential 110 line or zone and then puncture its wall along said line to an extent to sufficiently weaken the connecting section so that the weight of said part exceeds the adhesion along said line 115 and said part drops off.

3. The method of severing glass articles having forms of rotation, which consists in taking such an article while it is substantially uniform in temperature and rotating it about its own axis while maintaining that axis stationary, and, while so rotating the article, melting the glass along a circumferential line so quickly that severance results and leaves the glass constituting the severed edge of the article in substantially its original position with regard to the portion of the article to which it is attached. 120

4. The method of cutting off the waste end of the neck of a glass lamp bulb at one setting and in a single operation which com- 125

prises supporting said bulb so that its main axis is vertical and said waste end is lowermost; rotating said bulb and its support about a fixed vertical axis that coincides with 5 said main axis; and, during such rotation, directing flames against said neck and thereby by melting the glass along a desired line of severance so quickly that severance results and leaves the glass constituting the 10 severed edge of the finished article in substantially its original position with regard to the portion of the said article to which it is attached.

5. The method of cutting off the waste end 15 of the neck of a glass lamp bulb at one setting and in a single operation which comprises supporting said bulb so that its main axis is vertical and said neck is suspended and said waste end is lowermost; rotating 20 said bulb and its support about a single fixed vertical axis that coincides with said main axis; and, during such rotation, directing oxidizing flames against said neck adapted to heat the latter along a circumferential 25 line and thereupon puncture said neck along the same line until the weight of the waste end exceeds the adhesion along said line and said end drops off.

6. Apparatus for cutting off the end of a 30 tubular glass article, comprising a burner having a base, a standard rising vertically from the base at each end thereof, a plurality of nozzles removably attached to each standard and directed towards a common center 35 between the standards, there being passages in the base and standards leading to the several nozzles, an article carrier mounted upon a vertical axis at one side of said burner, a plurality of devices on the carrier each 40 adapted to carry an article with its axis vertical and at a distance from the axis of the carrier equal to the distance of said common center from the axis of the carrier, means for intermittently rotating the carrier, and 45 means for rotating an article in the carrier while the axis of said article is stationary and coincides with said common center.

7. Apparatus for cutting off the waste end 50 of the neck of a glass lamp bulb comprising, in combination, a chuck for supporting said bulb with the waste end thereof suspended below the chuck and so that the main axis of the bulb is vertical, means for rotating said chuck and the bulb carried thereby about the 55 main axis of the bulb while said axis is stationary, and a burner below said chuck for cutting off the waste end of said bulb comprising groups of symmetrically arranged nozzles disposed in a substantially horizontal 60 plane and adapted to project pointed flames radially of the axis of rotation of said bulb so as to practically just touch said bulb to

heat it along a circumferential cutting-off line at the juncture of said waste end and the bulb and then slit the wall of the latter along 65 said cutting-off line to an extent to sufficiently weaken the connecting section so that the weight of said waste end exceeds the adhesion along said line and said waste end drops off. 70

8. Apparatus for cutting off the waste ends 75 of the necks of glass lamp bulbs comprising, in combination, a table or support, a burner mounted on said support and comprising spaced vertical members joined by horizontal members to form a header, gas and cooling water passages in said vertical and horizontal members, groups of burner nozzles in the upper horizontal members of said header, such nozzles being disposed in a substantially horizontal plane and radially 80 with respect to the axis of said burner, means for supplying a gas mixture to said gas passages and nozzles, means for supplying cooling water to said cooling water passages, means for presenting glass lamp bulbs to said burner with the waste ends thereof lowermost, between said groups of nozzles, and with the main axes of such bulbs coinciding 85 with the axis of said burner, and means for rotating said bulbs about the axis of the burner whereby the gas flames from said groups of burner nozzles are adapted to heat 90 the neck of said bulb along a circumferential line at the juncture of said waste part therewith and then puncture the necks along such lines to an extent to sufficiently weaken the connecting section so that the weight of the waste part exceeds the adhesion along said line and said waste part drops off. 95

9. Apparatus for cutting off a part of a 100 tubular article comprising, in combination, a header having gas passages and gas outlets symmetrically arranged in the same plane about the axis of said header, water cooling 105 passages in said header, a gas supply device coupled to said header and adapted to supply gas to said gas passage and provided with a water-cooling passage, and connections between the water-cooling passage of said gas supply device and the water-cooling passage of said header whereby cooling water may be circulated successively through such passages. 110

10. The process of severing glass, which 115 consists in melting the glass along the line of severance so quickly that severance results and leaves the glass constituting the severed edge of the article in substantially its original position with regard to the portion of the 120 said article to which it is attached.

In testimony whereof, I affix my signature.

ROBERT J. KEHL.
